UNITED STATES PATENT OFFICE.

EDGAR H. CLARK, OF RICHMOND HILL, NEW YORK, ASSIGNOR TO WESTERN ELECTRIC COMPANY, INCORPORATED, OF NEW YORK, N. Y., A CORPORATION OF NEW YORK.

ELECTRICAL SWITCHING MECHANISM.

Application filed August 3, 1923. Serial No. 655,385.

To all whom it may concern:

Be it known that I, EDGAR H. CLARK, a citizen of the United States, residing at Richmond Hill, in the county of Queens and

5 State of New York, have invented certain new and useful Improvements in Electrical Switching Mechanisms, of which the following is a full, clear, concise, and exact description.

10 This invention relates to electrical switching mechanisms and more particularly to devices of this character employed in telephone exchange systems.

The object of the present invention is an 15 improved switching device for the interconnection of electrical circuits wherein speed and efficiency are combined with certainty and reliability of operation.

A feature of the invention is the provision, 20 in a switch for interconnecting lines and trunks wherein the usual interference prevention devices are eliminated to secure greater speed, of means for guarding against the taking into use of any parts of the 25 switch unless the connection can be successfully made.

A further feature relates to the provision, 30 in a coordinate switch where a plurality of operating magnets are energized in conjunction to effect a connection, of means for first preparing a circuit for each necessary magnet and then reducing the resistance of such circuits to permit the magnets to operate.

Other and further features contemplated 35 by this invention will be more fully understood from the following detailed description and also from the appended claims.

Referring to the drawing, the figure therein shown illustrates a portion of a switching device employed as a line switch for interconnecting subscribers' telephone lines with trunk circuits and in which the features of the invention are embodied. The switch 40 105 is of the coordinate type in which the incoming lines appearing in vertical rows are connectible to outgoing lines or trunks also appearing in vertical rows through the medium of horizontal link circuits. The contacts in the vertical rows are prepared 45 by vertical magnets which operate bars, one being provided for each row. The horizontal links with which connection is made by the prepared contacts of the several vertical rows are operated also by individual operating magnets and bars. The construction and

operation of a switch of this character is disclosed in the patent to Goodrum and Reynolds, No. 1,515,735, issued November 18, 1924.

The line switch 105 which serves to extend 60 incoming subscribers' lines in a telephone system to trunks which lead to other switches may have any desirable capacity. The illustration shows 4 subscribers' lines 100, 101, 102 and 103 incoming and appearing 65 in the vertical rows of contacts 112 and 113. The lines 101 and 103 both appear in the vertical row 112. The line 101 has access to a group of horizontal links including the 70 links 106, 107 and 108, while the line 103 has access to another group of horizontal links including links 109, 110 and 111. The lines 100 and 102 occupying the second vertical row 113 have access respectively to these 75 two groups of horizontal links. In a similar manner other groups of horizontal links may be provided in the same switch in which appear other subscribers' lines. Likewise, there may be as many vertical rows for receiving incoming subscribers' lines as desired. 80

In addition to the subscribers' lines, the switch 105 also contains a plurality of vertical rows of contacts representing outgoing 85 trunks. Two trunks, 137 and 138 only are shown occupying the vertical rows of contacts 114 and 115. It will be noted that each of the trunks has an appearance before every horizontal link in every group of the switch whereby any trunk may be reached 90 through the medium of any link.

It is customary practice to provide line switches and other preliminary switching devices in telephone systems with non-interfering circuit arrangements in order to eliminate as far as possible the likelihood of double connections. Many plans have been suggested and worked out for accomplishing this purpose. To prevent a double connection, however, it is necessary to provide additional equipment and circuits and sometimes to regulate the order and degree of availability with which calling lines may appropriate trunks. In the present arrangement the switch to a large extent is 100 freed from these additional circuit complications. This has been done in order to speed up the operation of the switch and to give each and every line an equal opportunity with all others in obtaining connection to 105 110

an outgoing trunk. Although remote, there is a possibility that on rare occasions, two subscribers calling simultaneously may have their lines connected to the same trunk, in which case it would be required that they hang up their receivers and again initiate the call in order to get a clear connection.

To guard against the possibility of a double connection while at the same time retaining all the advantages to be had in a switch where the complicated non-interfering equipment is provided, the present invention is so designed that the several operations which take place sequentially are not commenced until it has first been ascertained that the connection will be successful. In other words, the switch is not started in operation in response to a call, unless it is known that once having started, it may continue to a successful completion. A detailed description of the operation of the switch and its related circuits will now be given.

For this purpose, assume that the subscriber of line 101 wishes to initiate a call. On removing his receiver from the switch hook, a circuit is completed from battery to the winding of line relay 120, inner contact of cut-off relay 121, over the ring conductor of the line and returns over the tip conductor through the outer contact of relay 121 to ground. Relay 120 operates and a circuit is completed from battery through the winding of the vertical operating magnet 116, conductor 144, outer contact of relay 120, conductor 145, through the windings of relay 122 to ground. The relay 122 operates but the combined resistance of its windings is so great that the vertical operating magnet 116 cannot operate. Furthermore, a circuit is closed from battery, through the winding of vertical operating magnet 118, assuming the first trunk 137 to be idle, upper back contact of trunk relay 135, conductor 147, inner contact of line relay 120, conductor 146, through the windings of relay 123 to ground. Relay 123 operates, but due to its resistance, the vertical magnet 118 does not receive sufficient current to operate. Thus, on the operation of the line relay 120, the relays 122 and 123 are included in series with the vertical operating magnets to test the windings and circuits of these magnets. Since they are found in operable condition, the relays 122 and 123 operate but the magnets are prevented from operating at this time due to the high resistances of the relays.

It may be noted at this time that the relays 122, 123 and 124 are common to the group of horizontal links containing the links 106, 107, 108, etc., before which the calling line appears. In a similar manner, relays 127, 128 and 129 are common to the other group of horizontal links shown.

With relays 122 and 123 operated jointly,

a circuit is closed from ground through the contact of relay 123, windings of relay 124, outermost contact of relay 122, conductor 148, front contact of relay 130, assuming the first horizontal link 108 to be busy, back contact of relay 131, assuming the link 107 to be idle, right hand winding of the horizontal operating magnet 133 to battery. The relay 124 actuates in this circuit, but due to its resistance, sufficient current will not flow to operate the horizontal magnet 133. Thus, the operation of relay 124 serves as an indication that there is an idle horizontal link in the desired group over which connection may be had and that the circuit and winding of the operating magnet for this link are in proper condition. However, the horizontal magnet is not operated at the time.

Relay 124 in operating, modifies the circuits of the vertical magnet 116 and 118 in such a manner as to appreciably diminish the resistances in order to permit these magnets to operate. For example, the circuit of the vertical magnet 116 may now be traced over conductor 144, contact of relay 120, conductor 145, right-hand winding of relay 122, outer right-hand contact of relay 124 to ground at the contact of the slow operating relay 134. The left-hand winding of relay 122 having been excluded, the vertical magnet 116 receives sufficient current and operates to prepare all the contacts in the vertical relay 112. The circuit of magnet 118 which is also modified, may now be followed over the conductor 147, through the contact of relay 120, conductor 146, left-hand winding of relay 123, inner right contact of relay 124 to ground at the contact of relay 134. The right-hand winding of relay 123, having been excluded from the circuit, the magnet 118 operates to prepare all contacts in the vertical row 114. When both vertical magnets 116 and 118 operate jointly, the circuit of the horizontal operating magnet 133 is modified so that it now extends from battery through the right-hand winding of said magnet, thence over conductor 148 through the outermost contact of relay 122, right-hand winding of relay 124, left contact of said relay, conductor 149, contact of magnet 116, upper contact of magnet 118 to ground. The left-hand winding of relay 124 is excluded from this circuit and consequently the resistance in series with magnet 133 is reduced to such an extent that the magnet becomes operated.

Returning to the point where the vertical operating magnet 118 is energized, a circuit may be traced from ground through the lower front contact of said magnet, thence over the sleeve conductor 150 of the trunk 137, back contact of slow release relay 142, outer contact of relay 151, winding of relay 143 to battery. Relay 143 in any suitable

manner may serve to initiate the operation of another switch similar to the switch 105, as for the purpose of associating the trunk 137 with a central office sending mechanism. 5 Relay 143, in operating, locks through its winding and inner contact through ground at the outer right back contact of relay 139. Relay 143 also closes a circuit for the slow release relay 142. Relay 142 operates and 10 through its front contact applies a holding ground potential to the sleeve conductor 150 of the trunk. Later, when the horizontal operating magnet 133 is operated as described, the connection is extended from 15 the line 101, over the horizontal link 107 to the idle outgoing trunk 137. Immediately that this connection is effected, a circuit is closed from battery through the windings of magnet 133, winding of relay 20 131 over the test conductor of the link 107 through contacts of switch 105 to the grounded sleeve conductor 150. Relay 131, however, does not operate at this time since 25 it is shunted by the original operating circuit of magnet 133 which leads to ground through the contacts of the vertical magnets 116 and 118.

It will also be noted that when magnets 30 116 and 118 were operated to apply ground potential to the conductor 149, a circuit was thereby completed for the relay 134. Relay 134 being slow to operate, requires an interval in which to attract its armature. When, however, relay 134 finally operates, it 35 removes ground potential from the contacts of relay 124. This includes the secondary windings of relays 122 and 123 in the circuits of the vertical operating magnets 116 and 118 and consequently these magnets become deenergized. As soon as the vertical 40 magnets 116 and 118 release, direct ground is removed from the conductor 148 and the shunt around the winding of relay 131 is consequently opened. Hence, relay 131 operates in series with magnet 133 and both are 45 locked to the grounded sleeve conductor 150 through contacts of relay 142. Relay 131 in operating, extends the start wire 148 through to the horizontal magnet of the 50 next link circuit in order that this circuit may now be taken for the establishment of a subsequent connection.

At the time the switch is operated a circuit is also closed from the grounded conductor 150 through the contacts of the switch over the sleeve conductor 152, winding of cut-off relay 121 to battery. Relay 121 operates and opens the circuit of relay 120 which in turn disconnects the control 55 relays 122 and 123 and these relays become released.

As soon as the vertical operating magnet 60 118 releases when the connection is effected, a circuit is closed from ground over conductor 150 through the lower back contact

of magnet 118, upper winding of relay 135 to battery. Relay 135 operates and extends the start conductor 147 through to the next vertical operating magnet 119. If the next trunk 138 happens to be busy, relay 136 will 70 be operated in a similar manner and the start conductor is extended still further to the next trunk.

As soon as the subscriber's line 101 is extended through the line switch 105 to the 75 left-hand windings of the repeating coil 140 in the trunk 137, the supervisory relay 141 is energized. Relay 141 at its contact closes a substitute circuit for the slow relay 142, relay 143 having deenergized to open the 80 original holding circuit.

When the connection is no longer required, the calling subscriber by replacing his receiver on the switchhook opens the circuit of the supervisory relay 141. Relay 141 releases and opens the circuit of slow 85 relay 142. After an interval, relay 142 deenergizes and removes ground from the holding conductor 150, whereupon the magnet 133 and relay 131 become deenergized and the connection through switch 105 is released.

Should one of the lines 100 or 102 in the 90 vertical row 113 initiate a call, the vertical operating magnet 117 would be taken into use in connection with one of the trunk vertical magnets 118 and 119 in a manner identically the same as that already described in detail.

Where the start wire 147 depends upon the 95 contacts of the trunk relays 135, 136, etc., it is necessary to preserve the continuity of this start wire should a preceding trunk become idle at the instant when one of the succeeding trunks was being taken into use. To this end, a common relay 153 is provided. If the trunk 137, having been previously engaged, is released at the instant the succeeding trunk 138 is being taken for use, the relay 135 if permitted to release would disrupt the start wire 147. The instant the trunk 137 becomes idle, ground is removed from conductor 150 and the upper winding of relay 135 is deenergized. Since, however, at 100 this time, the start wire 147 is grounded, a circuit is closed from battery through the contact of relay 153, lower winding and inner lower contact of relay 135 to the 105 grounded conductor 147. Therefore, the relay 135 is held energized temporarily to preserve the start wire 147 until the succeeding trunk has been fully selected.

Should all trunks be simultaneously busy, a circuit is closed from battery through the 110 winding of relay 153, over the lower front contacts of relay 135, 136, etc. in series to ground.

For an understanding of the general manner in which the trunks may be extended to 115 senders and for other details not disclosed

herein, reference is made to the patent to S. B. Williams, No. 1,517,331, issued December 2, 1924.

What is claimed is:

- 5 1. The combination in a switching device of a plurality of operating magnets coacting jointly to effect a connection, means for closing circuits for each of said magnets without operating the same, and means for thereupon altering said circuits to permit said magnets to operate.
- 10 2. The combination in a switching device of a plurality of operating magnets coacting with each other to effect connections, means for closing circuits for each of said magnets without operating the same, and means for modifying the resistances of said circuits to permit said magnets to operate.
- 15 3. The combination in a switching device of a plurality of operating magnets coacting with each other to effect connections, means for preparing circuits for each of said magnets to ascertain if they are operative, said magnets remaining inert in said circuits, and means for thereupon altering said circuits to decrease the resistances thereof to permit the operation of said magnets.
- 20 4. The combination in a switching device of a plurality of operating magnets coacting jointly to establish connections, means for preparing circuits to test the condition of said magnets without operating the same, and means responsive to the test for thereupon altering said circuits to cause the operation of said magnets.
- 25 5. The combination in a switching device of a plurality of electromagnets coacting jointly to effect connections, means for preparing circuits for said magnets without actuating the same, means for testing the condition of said circuits, and means responsive to the test for thereupon altering such circuits to cause the operation of said magnets.

6. The combination in a switching device of a plurality of operating magnets coacting jointly to establish a connection, means for closing circuits for each of said magnets without operating the same, and means for altering the resistances of said circuits to permit said magnets to operate in a definite order with respect to each other.

7. The combination with incoming lines and outgoing lines of a switching device including link circuits for interconnecting said lines, electromagnets coacting with each other to operate said switching device, means for closing circuits for each of said magnets without operating the same, and means after the circuits have been prepared for altering the same to permit said magnets to operate.

8. The combination with incoming lines and outgoing lines, of a switching device having link circuits for interconnecting the incoming lines and the outgoing lines, a plurality of magnets cooperating to actuate said switching device, means for preparing circuits for said magnets to determine if there is an available link and an available outgoing line, said magnets remaining inert to said circuits, and means for altering the circuits to permit the operation of said magnets.

9. A switching device having vertical rows of contacts, lines appearing in said vertical rows of contacts, trunks appearing in other of said rows, link circuits for interconnecting said lines and trunks, a plurality of magnets cooperating with each other to actuate said contacts for effecting a connection, means for closing circuits for said magnets without operating the same, and means for modifying said circuits to cause the operation of said magnets.

In witness whereof, I hereunto subscribe my name this 27 day of July, A. D., 1923.

EDGAR H. CLARK.
